TENSION DEVICE FOR LOOM-SHUTTLES.

1,162,215.

Specification of Letters Patent. Patented Nov. 30, 1915.

Application filed January 11, 1911. Serial No. 601,996.

To all whom it may concern:

Be it known that I, PHILIPPE BOISVERT, a subject of the United Kingdom of Great Britain and Ireland, residing at Lowell, in the county of Middlesex and Commonwealth of Massachusetts, have invented a certain new and useful Improvement in Tension Devices for Loom-Shuttles, of which the following is a specification.

10 This invention relates to tension devices for loom-shuttles and its object is to provide means for accurately regulating the tension on the yarn as may be desired or required by the size and strength of the yarn, to make 15 the pull on the yarn steady and uniform and thus to prevent kinking of the yarn, catching of the yarn on the weft-fork and consequent breakage of said yarn and bending of said fork.

20 The use of my device renders it unnecessary to dampen the yarn, a common practice which causes bobbins to warp and split. This device does not collect lint and may be regulated so as to allow small knots to pass 25 through without breaking the yarn. To vary the tension, it is not necessary to substitute one spring for another, but merely to alter the tension of the spring. The yarn held under tension is more easily cut by the 30 feeler cutter of the well-known Draper loom.

My tension device is shown in connection with the self-threading means shown and described in United States Patent No. 783,538, granted February 28, 1905, to Northrop, but said device may be used with any self-threading shuttle or hand-threading shuttle provided with a suitable block in which said device may be held.

35 In the accompanying drawing, Figure 1 is a plan of the delivery-end portion of a shuttle containing my improvement; Fig. 2, a front elevation of the threading block detached and containing my improvement; Fig. 3 a rear elevation of the same; Fig. 4, 40 an elevation of my device on the side at which the thread leaves the device; Fig. 5, is a central section of said tension device; Fig. 6, a plan of the same.

The shuttle-body A, Fig. 1, provided with 45 a chamber a ; a delivery-eye a^1 and a cavity a^2 which receives the threading block B and

furnishes the passage for the yarn from the tip of the bobbin C to the delivery-eye a^1 are all of the usual construction.

The threading-block B is provided with a 55 longitudinal thread-passage indicated by dotted lines in Figs. 2 and 3 at b and at the top with a slit b^1 through which the thread is introduced into said passage substantially as shown in said Northrop patent. I provide 60 the block with a transverse hole b^2 in the shape of an inverted arch in which my tension device is arranged.

My tension device consists of a case D preferably of sheet metal bent into the form 65 of a U or an inverted arch and of a size and shape to fit the hole b^2 and to extend through said block from side to side of the same and I provide said case D at one end with ears d^1 which enter corresponding 70 shallow recesses b^3 b^4 in the side of the threading-block to prevent said case from being pushed too far into said block, as shown in Figs. 3 and 4.

Within the case are arranged two tension 75 pieces E F, the piece E being rigidly secured within said case and the piece F being movable with respect to the piece E. The piece E may be retained in place in the case D by rivets e^1 and at the outer lower 80 end is provided with a recess to receive a spring G and a pin H, the head h of which does not extend outside of the case and the shank h^1 of which is surrounded by the spring G, represented as a spiral wire 85 spring, and passes freely in a horizontal direction through the lower part of the piece E and into or through the piece F in which it is retained by a set-screw I which runs down vertically through the top of said 90 piece F and thrusts against the shank of the pin H in such a manner that the expansion of the spring G will draw the inner face of the piece F toward the inner face 95 of the piece E with a force dependent upon the compression of the spring. The tension of the spring G may be varied by loosening the set-screw I and pressing the head h of the pin and the piece F toward 100 each other until the desired tension is obtained and then setting the screw. The contiguous faces of the tension-pieces E F are

substantially parallel and inclined downward away from the head of the tension-pin H. The head of the set-screw I descends below the top of the movable tension-piece 5 F to avoid any possibility of the yarn catching thereon. The lower end of the tension-piece F is provided with a projection f which extends under a shoulder e² on the stationary-piece E to give a greater bearing surface to the bottom of said piece F, the top of said projection and the bottom of said shoulder being parallel with the tension-pin to guide said piece F. The faces of the case D are cut away on both sides at d² d³, to 10 allow the yarn to pass between the tension-pieces without contact with the case.

When the tension-piece is inserted in a threading-block and the latter is placed in the shuttle-body, said case is prevented from 15 movement by the ears d d¹ and the sides of the cavity which holds the threading-block.

When the shuttle is threaded in the usual manner, the yarn is drawn down in the act 20 of threading between the tension-pieces which are rounded off on their inner faces at the top e³ f² to allow the thread to enter the space between said tension-piece without difficulty.

30 I claim as my invention:—

1. The combination in a loom-shuttle having a longitudinal thread passage, of tension pieces arranged parallel, with said thread passage, one of said pieces being 35 fixed and the other movable, to admit a thread between said pieces, one of said pieces having a recess, a spring arranged in said recess, a pin passing freely through said spring and said last-named piece and 40 into the other of said pieces to compress said spring to vary the tension thereof, and means carried by said last-named piece to retain said pin from movement therein.

2. The combination in a loom-shuttle having a longitudinal passage, of tension pieces arranged parallel with said thread passage, one of said pieces being fixed and the other movable, to admit a thread between said pieces, one of said pieces having a recess, a 45

spring arranged in said recess, a pin passing freely through said spring and said last-named piece and into the other of said pieces to compress said spring to vary the tension thereof, and a set-screw turning in said last-named piece and thrusting against said pin to retain said pin from movement in 55 said piece.

3. The combination in a loom-shuttle, provided with a cavity, with a threading-block arranged in said cavity and having a longitudinal thread-passage and a hole transversely of said passage and having depressions, of a case adapted to fill said hole and in use to be retained therein by the sides of said cavity and having ears to enter the 60 depressions in said block, tension-pieces, one of which is rigidly in said case and the other of which is movable therein, the adjacent faces of said tension-pieces being parallel with said thread-passage, and a spring 65 to force said movable piece toward said rigid piece.

4. The combination in a loom-shuttle of a threading-block having a longitudinal thread-passage and a hole transversely of 70 said passage, a case adapted to fit said hole, tension-pieces arranged in said case, one of said pieces being rigidly secured in said case and having a transverse hole and a recess at the outer end of said hole and concentric 75 with said hole, and having a shoulder, and the other of said pieces having a projection which extends under said shoulder and bears on the under surface thereof, a tension-pin parallel with the contiguous surfaces of said 80 shoulder and projection and adjustably secured in said last-named tension-piece and extending through said transverse hole into said recess and having a head within said recess, and a spring compressed between said 85 head and the bottom of said recess.

In witness whereof, I have affixed my signature in presence of two witnesses.

PHILIPPE BOISVERT.
